RESIN CASTING MOLD

James L. Brannon, Plainfield, and Stephen A. Mraz, Perth Amboy, N. J., assignors to Bakelite Corporation, a corporation of New Jersey

Original application December 20, 1938, Serial No. 246,778. Divided and this application January 27, 1942, Serial No. 428,340

5 Claims. (Cl. 18—39)

This invention relates to the casting of resins and molds for that purpose.

In a copending application Serial No. 246,778, filed December 20, 1938, now Patent No. 2,273,926, there is described the preparation of dip or slush molds by means of arbors, the mold so obtained and the casting of resins therein; the claims of that application are directed to the arbor. This is a division of that application and is more particularly directed to the molds and the casting of resins therein.

Cast or turnery resins are customarily made by pouring liquid resins into shaped molds formed by the dipping of a master mold or arbor into molten lead or alloy metals and the freezing of the molten metal on the relatively cold arbor. The shell of metal frozen on the withdrawn arbor is jarred loose or stripped therefrom to give a mold commonly called a slush mold.

As heretofore made, each unit slush mold comprises one or more open top individual forms depending from a plate about which there is an upstanding rim. The presence of the rim or bounding strip of metal follows from the type of arbor used which consists of a backing plate from which the fingers (or positives) project; in the dipping of such an arbor it is necessary to partially immerse the backing plate to insure a continuous shell, or negative, and it is the lead which rises around the sides of the backing plate that forms the rim. Such a rim varies in height and thickness, depending on the depth and length of time of immersion; but it is usually thin, easily distorted and irregular in shape. In a casting operation the upstanding rim, if it has not become crimped or bent, serves to confine the resin that necessarily is poured in excess on the top of the mold; it is therefore regarded as forming an overflow chamber.

The commercial practice of casting resins consists in pouring each unit slush mold or shell individually from ladles; and with such a practice the overflow chamber is useful and necessary for preventing spillage of resin over the sides. The excess of resin retained in the overflow chamber is usually scraped over into adjacent unfilled molds during the pouring operation. Pouring of resin into a hand ladle and then filling the molds individually and scraping the excess from each, however, is a slow and tedious operation; not only does it demand considerable manual labor, but it delays the pouring while all the time the resin in the kettle is thickening to make the pouring and the removal of bubbles formed in the castings increasingly difficult.

A further disadvantage of present commercial practice is that the castings in the molds, after hardening in an oven, must be separately ejected from each mold by hammering. Ejection in automatic machinery has not been successful because the presence of the irregular overflow chamber, the non-uniformity of the molds, and the lack of strength of the top section make it almost impossible to center and support the molds in a press for multiple ejection.

The present invention provides molds which can be handled or made use of in ways that are not possible with rim molds as made heretofore. Furthermore surprising economies of operation can be obtained; in fact manufacturing costs of resin castings have been lowered to less than half by their means. In the main the molds are distinctive in having skirts or sides depending from flat ledges encompassing open top molds, and they possess the three major characteristics of a flat top, uniformity of contour and rigidity or strength; it is these characteristics in combination that in turn have made possible the changes in processing with consequent far reaching economies in producing castings. Arbors for the preparation of such molds are described and claimed in the parent application.

In the accompanying drawings:

Fig. 1 is a perspective view of a number of unit casting molds arranged in a stack or group for the casting of resin;

Fig. 2 is a perspective view partly in vertical section of a unit casting mold and illustrating as well resin castings in the individual forms;

Fig. 3 is a perspective view of a mold similar to that of Fig. 2 but with a closer spacing for the casting cavities;

Fig. 4 is a perspective view of a mold in which the casting cavities are annular in cross section for casting tubes;

Fig. 5 is a vertical section on line 5—5 of Fig. 4; and

Fig. 6 is a perspective view of a gang ejection means with a mold mounted therein.

A unit mold, as shown in Figs. 2 and 3 comprises a flat top 10 from which extend the negatives or individual casting shells 11 having the open top molding cavities; the cavities may be of any cross section as circular, polygonal, etc. Bounding the edge of the top 10 are the flat straight sides or skirts 12, and these are preferably of a depth and thickness to act as reinforcing beams to the top with the metal bridging over as at 14 between the skirt and a shell to provide a solid structure that resists distortion.

The top 10 can have a periphery of any configuration, but preferably it is a regular polygon in contour—triangular, square, hexagonal etc.—so that a number of unit molds can be grouped together to form a composite mold as illustrated in Fig. 1.

The unit molds are conveniently assembled or racked upon a large flat surface as a table top or plate 28; because of their regularly contoured flat tops they fit into each other to form a continuous flat surface perforated by the cavity openings. About the exposed sides of the assembled molds there can be drawn and secured a strip 22, such as a gum paper, a metal tape or a removable frame, to form a retaining wall and prevent spillage of resin.

For casting a resin, the assemblage of molds on the plate can be rolled under a still or kettle 38 containing the liquid resin with a discharge pipe 36 controlled by a valve 32 and a filter bag 33 on the end of the pipe to separate any sediment. Preferably one end of the mold assembly is placed under the discharge opening and the valve is opened for the flow of resin. The resin is first permitted to strike a solid part of the top 10, so that it runs by gravity over the surface into the nearest mold cavities 12; as these cavities become filled, the whole assemblage is slowly rolled under the still discharge to have a mass of liquid resin on the top flowing thereover and into additional mold cavities. With the movement of the assembly, surplus resin on the top is pushed by the scraper 35 to flow into unfilled cavities; by this means there is no excess of resin accumulating on the tops 10 of the molds. The labor and time for this operation is but a small fraction of that demanded by the use of hand ladles and the pouring of the individual molds.

There are additional advantages in this method of casting. In the pouring of resin by a ladle into the molds, the castings commonly contain bubbles which have been introduced in the pouring operation and have not risen to the top; but by running a continuous bubble-free stream of resin directly from the kettle to the molds, the fluid mass on the top flows by gravity, assisted by the scraping action, over the edges into adjacent mold cavities and air bubbles are not formed in the castings. Also the more rapid and continuous flow of resin from the still or reaction kettle promotes the uniformity of the castings; and the entire still content, which may be as large as several thousand pounds, can be utilized quickly in the one casting operation. Less of resin through spillage is obviated, since the resin does not leak to any substantial extent in the narrow crevices between the unit molds during the brief period of time that the resin flows or is pushed over the crevices. A more thorough scraping of the resin from the top of the molds is also made economically practical by this method and brings about a further saving of resin.

A form of unit mold is shown in Fig. 3 in which the mold cavities 40 have solid separating walls 41. This gives a sturdier and less distortable mold; and the bottom 42 is substantially level and even.

In Figs. 4 and 5, a similar type of mold but having an annular casting space is illustrated. The mold has the flat top 10 and skirt 18, but the annular casting cavity 58 is enclosed by the external wall 51 and the internal wall 52. Such

a mold is obtained with an arbor in which the depending positives or fingers are tubes.

The molds when filled with the viscous resin are placed in ovens and heated at temperatures and for periods of time that cause the resin to set or cure to a hardened state; this is illustrated by a cast article 66 in Fig. 2. The hardened castings are then removed from the molds.

With molds as herein described the removal of castings from the mold can be much simplified. The customary methods are manual operations; simple or highly tapered shapes are usually hammered out by striking the bottom 61 of the mold cavity with a mallet, and when this is not practical an air hammer and pin are commonly used to eject each casting separately. Ejection by a press has heretofore been impractical and generally impossible because of the weak upstanding rim of the overflow chamber, the non-uniformity of the molds and the lack of strength in the top section; non-uniformity in size and shape interferes with centering and holding the mold for the ejection pins to strike at the proper points and, since considerable force is required to penetrate the metal, a weak top section offers insufficient support. The molds of this invention, however, lend themselves to ejection in a press, for a top section of uniform contour permits inverting a mold and accurately centering it in a frame, and the flat sides of a mold act as a reinforcing beam for the top in the ejection process. When the mold is seated in the frame, the ejection is then readily accomplished by pushing a pin through the metal shell and into each mold cavity; all the castings of one mold can be ejected in one operation by using a spider having properly located pins. With a large number of cavities in a mold, it is preferable to stagger the length of the pins so that not more than about six to eight pins are penetrating the metal at one time because of the force required for penetration; distribution of pins of the same length in different sections of the mold is helpful in preventing mold distortion, because it eliminates excessive stress on any one part of the mold.

An ejection press with a frame for centering and supporting a mold is illustrated in Fig. 6 of the drawings. A frame 70 has a central opening 71 of the configuration and size of a mold top 10 provided with the skirt 18. A shoulder 72 extending into the opening forms a seat for the inverted mold. Vertical members 73 extend upwardly from the frame to hold a spider guide 74 adjustable thereon and secured in adjusted position by set screws 75; the forward edge of the spider guide is cut to show channels 76 for guiding ejection pins 77. The ejecting spider 60 consists of the pins carried by a plate 78 in proper spacing to strike the center of the bottom 61 of each mold cavity. The pins are shown of varying length to avoid simultaneous penetration of all the mold bottoms. The assemblage can be placed in any suitable press, as a hydraulic press, arbor press or mechanical punch press, so that a shaft 79 of the press engages the plate 78. On the downward stroke of the press the pins 77 are forced through the metal bottoms of the cavities, and the castings are dislodged and forced from the molds; the dislodged castings are collected in a receptacle placed beneath the opening 71. The spider guide 74, properly located on the vertical members 73, also acts as a stop to limit any upward movement of the mold and free it from

the ejecting pins on the return stroke of the press; for clarity of illustration the spider is shown in its retracted position, and a discharged casting 60 is shown in dotted lines.

What is claimed is:

1. A mold for the casting of resins comprising in combination a flat-surfaced top member, a shell depending from the member and providing a casting cavity opening at the surface of the member, and a depending skirt about the periphery of the top member to reinforce and rigidify the top member.

2. A mold for the casting of resins comprising in combination a flat-surfaced top member of a regular polygonal contour, a shell depending from the member and providing a casting cavity opening at the surface of the member, and a depending skirt about the periphery of the top member to reinforce and rigidify the top member.

3. A mold for the casting of resins comprising in combination a flat-surfaced top member, a shell depending from the member and having an open top casting cavity, a depending skirt

about the periphery of the member, and bridging connecting the skirt with the shell for reinforcing and rigidifying the top member.

4. A mold assembly for the casting of resins comprising in combination a plurality of molds having flat tops of regular contour fitting to each other laterally and longitudinally to form a substantially continuous flat surface, each of said molds having an open-top casting cavity and a reinforcing skirt depending from the peripheral edge of the top.

5. A mold assembly for the casting of resins comprising in combination a plurality of molds having flat tops of regular contour fitting to each other laterally and longitudinally to form a substantially continuous flat surface, each of said molds having an open-top casting cavity and a reinforcing skirt depending from the peripheral edge of the top, and a retaining wall about the 20 mold assembly.
